[57] CLAIM

The ornamental design for a vehicle drivers time log template, as shown and described.

DESCRIPTION

FIG. 1 is a front perspective view of a vehicle driver's time log template showing our new design;

FIG. 2 is a front elevational view;

FIG. 3 is a bottom plan view;

FIG. 4 is a right side elevational view;

FIG. 5 is a rear elevational view;

FIG. 6 is a top plan view; and

FIG. 7 is a left side elevational view thereof.
